UNITED STATES PATENT OFFICE.

GEORGE W. MILTIMORE, OF JANEVILLE, WISCONSIN.

IMPROVEMENT IN CAR-AXLE BOXES.

Specification forming part of Letters Patent No. 179,938, dated July 18, 1876; application filed May 1, 1876.

To all whom it may concern:

Be it known that I, GEORGE W. MILTIMORE, of Janesville, Rock county, State of Wisconsin, have invented a new and Improved Car-Axle, of which the following is a specification:

The accompanying drawing represents a vertical central section of my improved car-axle.

My invention relates to such improvements in that class of car-axles in which a stationary inner and a revolving outer wheel, carrying axle or sleeve, are employed, that the lubrication of the journal-box from the oil-reservoir is accomplished, to the exclusion of dust, the drip-oil collected, and the journal-box allowed to oscillate on the stationary axle to conform itself to a true bearing throughout, according to the spring of the axle produced by the weight of the car.

The invention will first be described, in connection with the drawing, and then pointed out in the claims.

In the drawing, A represents the stationary axle, which is rigidly connected with the spring or pedestal bearers or boxes B by horizontal locking-pins a. C is the revolving outer axle or sleeve, which is made of a laterally-connecting wrought-iron section, with end lips and wheel-carrying sections cast thereon. The journal-box D revolves with the sleeve on the stationary axle, and is lubricated from an air-tight oil-reservoir, E, of the pedestal-box, the reservoir being connected with the journal-box by a horizontal channel, b, and a vertical downward-extending channel, b', of the stationary axle. The vertical channel b' extends above the horizontal channel, and feeds the oil, by a vibrating and spring-acted pin, d, to the journal. The contact of the feeder-pin with the revolving journal-box, during the motion of the car, keeps the pin continually in motion, and admits, thereby, the entrance of small quantities of air into the channels, and through the same to the oil-receptacle.

The vibratory motion of the feeder-pin furnishes thus, mechanically, a small air-supply to the oil-receptacle, and allows, thereby, the feeding of a corresponding quantity of oil, which increases or decreases in proportion to the speed. When the car is at rest the oil ducts or channels are filled with the oil, but

the air-supply is discontinued, as the feeder-pin is also in a position of rest, and supplies no air, so that the oil is held suspended by the partial vacuum in the oil-receptacle, and prevented from running out. The surplus oil of the journal-box passes out through a closing nut or cap, F, screwed to the sleeve and encircling the axle. An annular rim or bead, e, of the cap F, conveys the drip-oil into a chamber or receptacle, B', of the pedestal-box, below the axle, from where it may be drawn off by a screw-plug. An oil-tight joint is formed between the pedestal-box and stationary axle by a tapering cork-disk, f, washer f¹, and perforated screw-plug f², preventing the oil from passing in or out between the pedestal-box and axle. A loose steel collar or ring, h, is placed on the stationary axle, between the pedestal-box and the revolving screw-cap of the outer axle, to provide for the wear caused by the lateral motion of the car, which is taken up between the pedestal-block and screw-cap at that point.

The journal-box D is made with a central convex part, and slightly downward inclined or tapering end parts. The outer axle or sleeve rests thereon by a corresponding annular concavity, and an outer ring, i, of iron, brass, or other material. The sleeve and ring are arranged, adjoining to the annular concave parts, with slight outwardly-inclined parts which form, with the tapering ends of the journal-box, narrow annular spaces that provide for the oscillating motion of the journal-box, when the weight of the car causes the springing of the inner axle. The journal-box is, thereby, always in full contact throughout its entire length with the inner axle, and compelled to wear out evenly.

The lubrication of the car-axle is accomplished in an economical manner, and the wearing out of the journal-box diminished, by distributing the friction throughout the length and circumference of the box, in consequence of the oscillating motion of the journal-boxes.

Having thus described my invention, what I claim as new, and desire to secure by Letters Patent, is—

1. The combination, with the pedestal-box, of the stationary axle, having a cork disk, washer, and hollow screw-plug, to form an

oil-tight joint between the pedestal-box and axle, substantially as herein shown and described.

2. The combination of the closing screw nut or cap of the outer revolving axle or sleeve, said cap having an outer rim or bead, with a drip-oil chamber below the stationary axle, substantially as herein shown and described.

3. The combination of the revolving journal-box, having a convex annular part and tapering ends with the annular concaved and inclined revolving sleeve, and intermediate

ring, to provide for the oscillating motion of the journal-box, substantially as herein shown and described.

4. The outer axle or sleeve, made of a lateral wrought-iron section, and cast-iron end sections, substantially as herein shown and described.

GEORGE W. MILTIMORE.
